(57) **CLAIM**

The ornamental design for a motion assisting device, as shown and described.

DESCRIPTION

FIG. 1 is a front view of a motion assisting device showing our new design;

FIG. 2 is a back view thereof;

FIG. 3 is a top view thereof;

FIG. 4 is a bottom view thereof;

FIG. 5 is a right view thereof, a left view being a mirror image thereof; and,

FIG. 6 is a reference front view thereof showing usage state.

(Continued)

In the drawings, the broken lines depict environment that forms no part of the claimed design.

1 Claim, 6 Drawing Sheets
